UNITED STATES PATENT OFFICE.

JAMES ARKELL, OF CANAJOHARIE, NEW YORK, ASSIGNOR TO THE
ARKELL & SMITH, OF SAME PLACE.

DESIGN FOR A BAG.

SPECIFICATION forming part of Design No. 29,595, dated November 1, 1898.

Application filed October 1, 1898. Serial No. 692,442. Term of patent 14 years.

To all whom it may concern:

Be it known that I, JAMES ARKELL, of Canajoharie, State of New York, have invented and produced a new and original Design for Bags, of which the following is a full, clear, and exact description, reference being had to the accompanying drawings, forming a part thereof.

In the drawings, Figure 1 is a view in perspective, and Fig. 2 is a view in section.

The leading feature of my design consists in a bag having the shape shown and provided with a raised or embossed surface consisting of diagonal dashes which coöperate

to give the appearance of wire or other netting.

A represents the bag, which is provided with a raised or embossed surface consisting of dashes B and intermediate flat and smooth portions C. The dashes B are so arranged as to represent wire or other netting.

What I claim is—

The design for a bag herein shown and described.

JAMES ARKELL.
